UNITED STATES PATENT OFFICE.

JOHN M. ELLISON, OF PITTSBURG, PENNSYLVANIA.

IRONING-TABLE.

SPECIFICATION forming part of Letters Patent No. 326,857, dated September 22, 1885.
Application filed January 15, 1885. (No model.)

To all whom it may concern:

Be it known that I, JOHN M. ELLISON, a citizen of the United States, residing at Pittsburgh, in the county of Allegheny and State of Pennsylvania, have invented certain new and useful Improvements in Ironing-Boards; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this invention, and is a vertical section taken on the lines *xx* of Fig. 2. Fig. 2 is a view of the under side of the board folded. Fig. 3 is a vertical section taken through the end of the board on the dotted lines *yy* of Fig. 2. Fig. 4 is a detail, and shows a top view of the iron-stand that is fastened to the board.

This invention has relation to ironing boards; and it consists in the construction and novel arrangement of devices, as hereinafter set forth, and pointed out in the appended claim.

In the accompanying drawings, the letter *A* designates the main ironing-board.

B is a transverse cleat, which is secured to the under side of said board near its head, and is designed to strengthen said board at this point, and to prevent warping.

C is a block or hinge bearing, which is bolted to the ironing-board. It bears against the transverse cleat, and its bolt or bolts *D* extend upward through the cleat and ironing-board. Above the ironing-board is an iron-holder, *E*, which is provided with a perforation, *F*, and with legs *G*, which are let into the board. A bolt, *D*, passing through the perforation *F*, serves to fasten the holder in place.

K K are short links, which are pivoted on the ends of a transverse bolt, *L*, which passes through the block or bearing *C*. To the lower ends of these links are pivoted the journals or ends of the bolt *m*, which is secured in the lower leg, *N*, of the board. This leg or support *N* is made tapering, and is flat on its

upper and lower surfaces, so that it can be used when necessary in pressing sleeves or the legs of trousers. The upper end, *P*, of this support is extended beyond the points where the links are connected, and the extremity of this end is finished obliquely to form a bearing, *s*, parallel, or nearly so, with the under surface of the board-extension *v* of the main board. In the bearing *s* are inserted several teeth, *t*. When the head-extension *v* of the main board is placed on the edge of a table or window-sill, and the support *N* is turned down to rest upon the floor, the extension *P* or upper arm of the lever-support rises under the table-edge or window-sill and forcibly engages the same, holding the head of the ironing-board in position. This fastening is made secure by means of the brace *Z*, which is usually hinged to the under side of the main board, and is designed to engage by its lower end one of the perforations or catches *a* of the lever-support. These catches are usually made in a strip of metal which is secured to the lever-support; but, if preferable, the brace-support *Z* may be hinged to the lever-support and the catches provided on the under side of the main board. The end of the brace should be provided with a sliding bolt to engage the catches or perforations *a*.

The links *K K* allow a free adjustment of the lever-support, both in regard to the height of the table or bearing to which the ironing-board is to be attached and in respect to the thickness of the table edge or bearing to which the clamp formed by the end of the board and the extension of the lever-support is applied.

Having described this invention, what I claim, and desire to secure by Letters Patent, is—

The combination, with the main board, its transverse cleat, and the block or bearing *C*, of the bolt *D*, connecting said board and bearing, the transverse bolt *L*, links *K K*, lever-support pivoted to said links, and the brace *Z*, substantially as specified.

In testimony whereof I affix my signature in presence of two witnesses.

JOHN M. ELLISON.
